UNITED STATES PATENT OFFICE.

EDWIN L. RUSSELL, OF DETROIT, MICHIGAN, ASSIGNOR, BY MESNE ASSIGNMENTS, TO
SILENT VALVE MOTORS CORPORATION, A CORPORATION OF DELAWARE.

VALVE.

1,284,463.

Specification of Letters Patent. Patented Nov. 12, 1918.

Application filed May 9, 1912. Serial No. 696,077.

To all whom it may concern:

Be it known that I, EDWIN L. RUSSELL, a citizen of the United States, residing at Detroit, in the county of Wayne and State 5 of Michigan, have invented a new and useful Valve, of which the following is a specification.

The object of my invention is to produce a rotary valve especially adapted for use in 10 controlling the flow of gases to and from an internal combustion engine.

The accompanying drawings illustrate 15 my invention. Figure 1 is an axial section of my improved valve, its casing, and an adjacent cylinder; Fig. 2 a horizontal fragmentary section on line 2—2 of Fig. 1; Fig. 3 an axial section of the valve at right angles to the section shown in Fig. 1; and Fig. 4 an elevation of the valve; and Fig. 5 20 a section of the valve similar to Fig. 1 but with the drive shaft omitted.

In the drawings, 10 and 11 indicate two adjacent cylinders of an internal combustion engine and 12 indicates a valve chamber, the 25 axis of which is conveniently parallel with the axes of the cylinders 10 and 11. The valve chamber 12 is conveniently round and axially tapered and communicates with the cylinders 10 and 11 through ports 13 and 14, 30 respectively, these ports, at the valve chamber end being of considerable length axially of the valve chamber, and, in practice, having an angular extent of about 20° and the two ports separated by a space of about 25° 35 around the valve chamber wall.

Rotatably mounted within the valve chamber 12 is a valve 15 which is, of course, fitted to the chamber and is preferably driven from the shaft 16 through the medium of a peculiar driving connection 17, or its equivalent, by means of which the valve is automatically uniformly maintained in its seat independent of variations in size of the valve and valve seat due to temperature or other changes. The peculiar driving connection 17 forms the subject matter 45 of my pending application, Serial Number 603,705.

Extended diametrically through the valve 50 15 is an exhaust passage 18, the ends of which are arranged to alternately and successively register with the ports 13 and 14. As the ports 13 and 14 serve both as inlet and outlet ports for their respective cylinders, an exhaust passage 19, which leads

from the valve chamber 12, is placed far enough below the lower ends of the ports 13 and 14 to provide for the surface 15' on the valve which will fit the valve chamber between the lower ends of the ports 13 and 14 60 and the upper end of the passage 19. The upper end of valve 18 is hollow, or tubular, as shown in Fig. 3, so as to provide a fuel inlet chamber 21 which is provided with diametrically opposed ports 22, 22 65 which also alternately and successively register with the ports 13 and 14.

It is desirable that the several passages be made as large and as unobstructed as possible and that the various walls or portions 70 of the valve which define the several passages shall be of as nearly uniform thickness as possible and that those walls be as thin as is consistent with proper strength and an accurate machining of the same. 75 For these reasons, and in view of the fact that the exhaust passage 19 is out of alignment with the ports 13 and 14, I have found it expedient to define the exhaust passage 18 by means of a hollow partition 27 substantially V-shaped in longitudinal section, as clearly indicated in Fig. 1, thus permitting the inlet chamber or passage 1 in the upper end of the valve to be of considerable volume, the said chamber extending down 80 alongside of the exhaust passage, as clearly indicated at 23 in Fig. 3 and also indicated by the dotted line 24 in Fig. 1, and thus making possible elongated inlet ports of maximum capacity and quick cut-off. By 85 90 this arrangement I form very thin valve walls 25 of considerable vertical extent and, in order to hold these walls against distortion, I provide a cross bar 26 which is cast integral with the valve and connects the two 95 walls 25, 25 at about their middles vertically, and this cross bar is preferably anchored to the partition 27 at the crotch of the V, formed thereby, thus permitting the cross bar to serve as a distributor of some of the 100 heat from the exhaust passage wall.

By the above construction I have been able to produce a short rotary valve having unusually large exhaust and inlet passages (as compared with the size of the valve) while 105 at the same time maintaining a gas-tight fitting of the valve in its casing. This arrangement of gas inlet chamber also surrounds much of the wall of the exhaust passage with fresh gases which will, of course, 110

absorb heat from the exhaust passage wall and thus assist in keeping the valve cool and in preventing warping.

The upper end of the valve chamber 12 is 5 capped by a cover 31 into which a fuel supply pipe delivers. Of course inlet and exhaust functions of the valve passages and coöperating parts might be reversed without departing from my invention, but I believe the 10 arrangement described to be the better.

I claim as my invention:

In an internal combustion engine, the combination with a pair of cylinders and an adjacent valve chamber with two 15 passages each forming a communication between the valve chamber and a cylinder, of a rotary valve mounted within the valve chamber and coacting with the valve-chamber ends of the aforesaid passages, said valve 20 having an open ended chamber provided with two oppositely-arranged ports arranged for successive registration with the

aforesaid cylinder passages, and said valve also having a gas passage leading transversely through the valve and defined by a 25 hollow partition V-shaped in longitudinal section and flanked by the chamber of the open end of the valve, said gas passage being arranged for successive registration at its ends with the aforesaid cylinder passages 30 and with a conduit communicating with one side of the valve chamber, a brace bar connecting the outer walls of the open end of the valve, and a conduit communicating with the valve chamber and the open end of the 35 valve.

In witness whereof, I have hereunto set my hand and seal at Indianapolis, Indiana, this twenty-second day of April, A. D. one thousand nine hundred and twelve.

EDWIN L. RUSSELL. [L. S.]
